STRIP APPLYING MACHINES

John Stanley Kellett and Kenneth Lawrence Moore, Leicester, England, assignors to United Shoe Machinery Corporation, Flemington, N.J., a corporation of New Jersey

Filed Jan. 23, 1962, Ser. No. 168,137

Claims priority, application Great Britain Feb. 4, 1961
3 Claims. (Cl. 12—67)

This invention relates to strip applying machines, and is herein illustrated as embodied in a machine for adhesively applying a welt to the overlasted margin of a shoe upper. It will, however, be understood that the invention is not thus limited in its utility.

In the manufacture of certain types of shoes it is customary to apply to the upper surface of the extension edge of the outsole a strip of material, simulating a welt, to enhance the appearance of the shoe. The strip may be of leather, rubber, plastic, or other suitable material.

A machine for adhesively applying such a strip is illustrated in United States Letters Patents No. 2,850,751, issued September 9, 1958 upon an application of Cyril H. James. In the machine of the James patent the work is supported on and fed by a roll mounted on a shaft, while the strip is applied to the sole margin by a frustoconical roll mounted on another shaft and rotated about an axis disposed at an angle to the axis of rotation of the work supporting and feed roll.

In recent years it has become the practice to attach, by means of adhesive, a welt around the feather of a shoe which has been inwardly lasted by adhesive. The welt is so shaped on the portion which is attached to the upper that the welt extends outwardly in a plane parallel to the shoe bottom.

The latter method has several advantages as compared with the previously described method, in that, in addition to enhancing the appearance of the shoe, it helps to keep out water from the welt crease and provides an additional bond between the sole and the upper.

It is an object of the invention to provide a machine of the type disclosed in the James patent previously referred to, but more particularly adapted for the adhesive attachment of a welt strip to the lasted margin of a shoe upper.

To this end, there is provided, in a strip applying machine, a rotatable work supporting and feed table, a roll engageable with one edge of a welt strip to press the strip inwardly against the lasted margin of the shoe upper, and a rotatable guide against which the shoe is held by the operator as it is being fed during a welt attaching operation. In accordance with a feature of the invention, the table, the welt pressing roll and the shoe guide are mounted upon a single shaft and rotate about a common axis, whereby the attachment of the welt and the feed of the work may be accomplished with a minimum expenditure of effort on the part of the operator.

The illustrated machine is also provided with a welt guide for controlling the welt to the point of application, and if the welt to be attached and/or the lasted margin of the upper are coated with a heat-activatable cement, a hotair blower may be provided for activating the cement immediately in advance of the point of application.

In the drawings,

FIG. 1 is a left side elevation, partly in section, of a machine embodying the invention;

FIG. 2 is a view in the direction indicated by the arrow II in FIG. 1; and

FIG. 3 is a view, to a larger scale than FIGS. 1 and 2, showing, in section, a portion of the welt attaching instrumentalities of the machine operating upon a shoe.

2

The machine is mounted on a column 2, in the base of which is a motor (not shown) which is arranged to drive a pulley 4 continuously by means of a belt 6. The pulley 4 is secured to a shaft 8 of a reduction gear unit 5 10, of conventional form, which is mounted on a rear portion of a two-armed bracket 12 secured to the column 2 by screws 14. The arms of the bracket 12 extend upwardly and have pivoted in their upper end portions by two pivot screws 16 (only one of which is visible in the drawings) a two-armed bearing bracket 18. The bearing bracket is thus adjustable angularly about the pivot screws 16 and is secured in the adjusted position by two locking screws 20 (one only of which is visible in the drawings). The locking screws are threaded one in each 15 arm of the bearing bracket 18 and extend outwardly through arcuate slots 22 (one only shown) in the arms of the bracket 12, the bearing bracket being secured by the locking screws in any position within the range allowed by the slots.

Journalized in a bridge portion 24 extending between the walls of the bearing bracket 18 is a spindle 26, the rearward end portion of which is coupled by means of a universal coupling 28 to an output shaft 30 of the reduction gear unit 10. The spindle 26 emerges upwardly through the bridge portion 24 to carry a disk-like table 32, to which a welt strip W is guided for attachment to the overlasted margin of a shoe upper S. The table 32 is secured to the end of the spindle 26 by a mushroom-headed screw 36 which acts as a shoe guide and is threaded into the spindle. Between the head of the screw 36 and the table 32 is secured a welt edge pressing roll 38 comprising a washer of a thickness slightly exceeding the thickness of the welt and of smaller diameter than the head of the screw. The periphery of the roll 38 is offset inwardly of the screw head a distance substantially equal to the distance the welt projects outwardly of the crease between the upper and the welt, the arrangement being such that the roll presses the welt against the overlasted margin of the shoe upper by engagement with its outer edge, while the shoe is pressed by the operator against the attaching face of the welt as it is guided by engagement with the head of the screw 36, as shown in FIG. 3.

For controlling the welt to the point of application, the machine is provided with a guide 40 comprising a lower lip 41 adapted to extend to the marginal portion 45 34 of the table 32 which is stepped below the central portion thereof to provide a continuous supporting surface for the work. Built on the lower lip 41 is a bridge piece which, together with the lower lip, forms a tunnel of 50 rectangular cross section through which the welt strip can just pass without undue friction. The guide 40 is carried by an arm 42 which is adjustably secured to the bearing bracket 18 by a screw 44 which extends through a slot 46 in the arm and is threaded into the bearing bracket.

55 In the operation of the machine, the welt W is fed, from a reel (not shown), through the tunnel of the welt guide, the end of the welt projecting through the welt guide into contact with the roll 38. The welt will conveniently have been coated on its shoe engaging surface with either a pressure sensitive cement or a heat activatable cement, as may also be the portion of the shoe upper to which the welt is to be attached. If a heat activatable cement is used, the machine may be fitted with a nozzle (not shown) through which hot air may be directed against the welt and the upper immediately in advance of the point of application of the welt.

With the welt in position to be attached to a shoe, the portion of the shoe upper at which the welt attaching is to commence is pressed against the welt and against the 70 head of the screw 36, which acts as a shoe guide, while the shoe is also held down by the operator against the sup-

porting table 32. Since the table, the roll 38, and the shoe guide 36 are continuously rotated, the shoe, with but little effort on the part of the operator, is fed until the required length of welt has been attached, the operator taking care to keep the shoe in contact with the shoe guide and the table, especially when operating around a curve, such as the toe end of a shoe.

Having thus described our invention, what we claim as new and desire to secure by Letters Patent of the United States is:

1. A machine for adhesively attaching a welt strip to the lasted margin of a shoe upper, comprising a rotatable spindle, means for driving said spindle, a table mounted on the spindle for supporting a shoe and a welt strip fed thereto and for feeding the work, a roll also mounted on said spindle and engageable with the outer edge of the welt strip to press the strip against the overlasted margin of the shoe upper, and a member secured to said spindle and engageable with the shoe to guide the same during the attachment of the welt strip.

2. A machine according to claim 1, characterized in that the welt edge pressing roll is offset inwardly of the periphery of the shoe guiding member a distance substantially equal to the distance the welt is to project from the crease between the welt and the shoe upper.

3. A machine according to claim 1, characterized by the provision of an adjustable guide having a tunnel portion of rectangular cross section through which the welt is guided toward the point of attachment to the overlasted margin of a shoe upper, said tunnel portion of said welt guide extending into a stepped marginal portion of the supporting table to provide a continuous supporting surface for the work.
